UNITED STATES PATENT OFFICE.

SIMEON C. DORLAND, OF OLYMPIA, WASHINGTON.

DRY-CLEANING MACHINE.

Application filed March 25, 1924. Serial No. 701,779.

To all whom it may concern:

Be it known that I, SIMEON C. DORLAND, a citizen of the United States, residing at Olympia, in the county of Thurston and State of Washington, have invented new and useful Improvements in Dry-Cleaning Machines, of which the following is a specification.

This invention relates to improvements in machines for cleaning clothes and other articles and has especial reference to machines used for what is commonly known as dry cleaning.

An object of the present invention is the provision of a combination dry cleaning and continuous clarifying machine wherein the cleaning fluid (such as a gasoline preparation) may be clarified or filtered during the process of cleaning clothes, so as to eliminate dirt and other impurities which have been removed from the clothes, after which the cleaning fluid is returned to the cleaning chamber of the machine for further use.

Another object of the invention is the provision of a combined machine for the purposes above stated, which is constructed as a unit, so as to occupy a relatively small space and permit of the use and re-use of the cleaning fluid without removing the same from the machine.

With the above and other objects in view, the invention further includes the following novel features and details of construction, to be hereinafter more fully described, illustrated in the accompanying drawings and pointed out in the appended claims.

In the drawings:—

Figure 1 is an elevation of a machine constructed in accordance with the invention.

Figure 2 is an end view thereof with the settling compartments and rotatable cylinder shown by dotted lines.

Figure 3 is a transverse sectional view of the machine.

Figure 4 is a section on the line 4—4 of Figure 2.

Figure 5 is a detail perspective view of the rotatable cylinder.

Referring to the drawings in detail where-
50 in like characters of reference denote cor-
responding parts, the reference character
10 indicates a casing which includes a sub-
stantially cylindrical cleaning chamber 11
and a longitudinally disposed reservoir 12,
55 the latter being disposed to one side of and
in communication with the cleaning cham-

ber 11. The cleaning chamber may be pro-
vided with a top or cover 13 which is leak-
proof, while the reservoir is provided with
an opening 14 which is normally closed by 60
a cover 15, whereby the gasoline or other
cleaning fluid may be placed within the res-
ervoir.

Mounted for rotation within the clean-
ing chamber 11 upon a shaft 16 is a cylin- 65
der 17, the latter being provided with an
opening whereby the articles to be cleaned
may be inserted within the cylinder. This
opening is closed by a door or closure 18,
the said door or closure and the cylinder 17 70
being perforated. Extending radially from
the inner wall of the cylinder are spaced
ribs or projections 18' which, when the cyl-
inder is rotated act to carry the articles
around the cylinder in a manner to stir up 75
or agitate the articles. The shaft 16 is pro-
vided with a pulley 19 which may be con-
nected with a suitable source of power.

The gasoline or other cleaning fluid is
placed within the reservoir and is conducted 80
to the cleaning chamber through pipes 20,
the latter being provided at one of their
ends with a screen 21 and having valves 22
to control the passage of fluid. After the
articles have been placed within the cyl- 85
inder, the latter is rotated so that the gasoline
will be passed through the articles, the gaso-
line being gradually and intermittently re-
turned to the reservoir by means of pockets
or troughs 23 which are carried by the cyl- 90
inder 18. The valves 22 being opened and the
valves 25 closed, the cleaning fluid will make
a continuous circuit from the cleaning cham-
ber 11 to the reservoir and back to said
chamber. This process of cleaning is con- 95
tinued for a short period until the cleaning
fluid acts on the dirt and grease in the cloth-
ing or other articles. After the lapse of this
short period the valves 22 are closed and
the valves 25 opened, whereupon the clean- 100
ing fluid will make a continuous circuit dur-
ing the remaining cleaning period, the fluid
passing from the bottom of the cleaning
chamber 11 through the troughs 23 so as
to be carried around the cleaning cham- 105
ber and deposited in the reservoir 12, pass-
ing from this reservoir through the pipes
24 into the bottom of the clarifying cham-
ber. After the articles have been cleaned
and the gasoline returned to the reservoir 12, 110
the said gasoline is subjected to a filtering
or clarifying action and for this purpose

- the casing includes a clarifying chamber 23' which is located below the cleaning chamber 11 and which is in communication with the reservoir 12 through the pipes 24. 5 Valves 25 control these pipes. The pipes 24 extend downwardly along the bottom of the clarifying chamber and the latter contains a suitable clarifying agent 26, through which the gasoline rises, the heavy dirt settling 10 to the bottom of the chamber 23' as indicated by the dotted line *a*, while the muck settles upon the top of the clarifying agent as indicated by the dotted line *b*. The purified gasoline which will occupy the remainder 15 of the chamber 23' will pass upward and through a series of small openings 27 into a lower settling compartment 28 and through this compartment and through a series of small openings 29 into an upper settling compartment 30, sediment which might be carried by the gasoline settling within these compartments. The gasoline then passes through a series of small openings 31 into the cleaning chamber for future use. 25 The pipes 24 extend longitudinally through the machine as shown in Figure 4 and are provided with perforations so that the gasoline will be distributed throughout the clarifying agent. 30 The clarifying chamber and the settling compartments 28 and 30 are each provided with draw-off cocks 32, while the clarifying chamber is provided with a normally covered clean-out port 33 and a drain cock 34. 35 The cleaning chamber is in communication with a sight gauge 35 which is located at one end of the machine, while a similar gauge 36 is provided for the clarifying chamber. 40 The casing is preferably supported upon legs 37.
- The invention is susceptible of various changes in its form, proportions and minor details of construction and the right is hereinafter reserved to make such changes as properly fall within the scope of the appended claims.
- Having described the invention what is claimed is:-
- 50 1. A machine of the class described embodying a casing, a cleaning chamber within the casing, a perforated cylinder rotatably mounted therein, a fluid reservoir, means whereby fluid may be conducted from the reservoir to the cleaning chamber and means controlled by the rotation of the cylinder for returning the fluid to the reservoir. 55 2. A machine of the class described embodying a casing, a cleaning chamber within the casing, a perforated cylinder rotatably mounted therein, a fluid reservoir, means whereby fluid may be conducted from the reservoir to the cleaning chamber and means carried by the cylinder for returning the fluid to the reservoir. 60 3. A machine of the class described embodying a casing, a cleaning chamber within the casing, a perforated cylinder rotatably mounted therein, a fluid reservoir, means whereby fluid may be conducted from the reservoir to the cleaning chamber and pockets included in the cylinder for returning the fluid to the reservoir. 70 4. A machine of the class described embodying a casing, a cleaning chamber within the casing, a perforated cylinder rotatably mounted therein, a fluid reservoir, means whereby fluid may be conducted from the reservoir to the cleaning chamber, means controlled by the rotation of the cylinder for returning the fluid to the reservoir, fluid clarifying means, means whereby the fluid may be conveyed from the reservoir to the clarifying means and means for returning the clarified fluid to the cleaning chamber. 75 80 5. A machine of the class described embodying a casing, a cleaning chamber within the casing, a perforated cylinder rotatably mounted therein, a fluid reservoir, means whereby fluid may be conducted from the reservoir to the cleaning chamber, means controlled by the rotation of the cylinder for returning the fluid to the reservoir, fluid clarifying means, means whereby the fluid may be conveyed from the reservoir to the 90 95 clarifying means, means for returning the clarified fluid to the cleaning chamber and settling compartments located within the casing between the clarifying means and the cleaning chamber and in the path of the 100 fluid. 105 6. A machine of the class described embodying a casing, a cleaning chamber within the casing, a perforated cylinder rotatably mounted therein, a fluid reservoir included in and disposed to one side of the casing, means for conducting fluid from the reservoir to the cleaning chamber and means controlled by the rotation of the cylinder for intermittently returning the fluid to the reservoir. 110 115 7. A machine of the class described embodying a casing, a cleaning chamber within the casing, a perforated cylinder rotatably mounted therein, a fluid reservoir included in and disposed to one side of the casing, means for conducting fluid from the reservoir to the cleaning chamber, fluid clarifying means and means for returning the clarified fluid to the cleaning chamber. 120 125 8. A machine of the class described embodying a casing, a cleaning chamber within the casing, a perforated cylinder rotatably mounted therein, a fluid reservoir, means whereby fluid may be conducted from the reservoir to the cleaning chamber, means controlled by the rotation of the cylinder for returning the fluid to the reservoir, a clarifying chamber located beneath the cleaning chamber, means for conducting 130

fluid from the reservoir to the clarifying chamber, settling compartments located between the clarifying and cleaning chambers and means for directing the clarified fluid 5 from the clarifying chamber through the settling compartments into the cleaning chamber.

9. A machine of the class described embodying a casing, a cleaning chamber with-

in the casing for receiving a cleaning fluid 10 and articles to be cleaned, a clarifying chamber, settling chambers and means whereby the clarifying fluid will be subjected to the action of the clarifying and settling chambers during the article cleaning process. 15

In testimony whereof I affix my signature.

SIMEON C. DORLAND.
